UNITED STATES PATENT OFFICE.

JOHN HEBERLING, OF ROCHESTER, NEW YORK.

SEWING-MACHINE.

1,118,417.

Specification of Letters Patent. Patented Nov. 24, 1914.

Application filed June 20, 1913. Serial No. 774,809.

To all whom it may concern:

Be it known that I, JOHN HEBERLING, of Rochester, in the county of Monroe and State of New York, have invented a new and useful Improvement in Sewing-Machines, which improvement is fully set forth in the following specification and shown in the accompanying drawings.

The present invention relates to sewing machines of the type employing a reciprocating needle bar having a dip and dwell therein for the formation of a loop for the passage of a reciprocating or vibrating shuttle, an object of this invention being to provide a needle bar mechanism which is inexpensive to manufacture, noiseless in action, and which obtains its greatest force during the passage of the needle through the goods.

Another object of this invention is to provide a take-up device which supplies the necessary amount of thread during the passage of the shuttle through the loop without giving an over-supply which is liable to be come entangled.

To these and other ends the invention consists in certain parts and combinations of parts all of which will be hereinafter described, the novel features being pointed out in the appended claims.

In the drawings: Figure 1 is a front end view of the head at the end of the bracket arm; Fig. 2 is a vertical section through the head showing the needle bar mechanism and take-up device in elevation; Fig. 3 is a view of the needle bar mechanism with the head plate removed, the needle bar mechanism being in the position which it assumes when the needle bar is in its uppermost position; Fig. 4 is a view similar to Fig. 3 except that the needle bar mechanism is shown in the position which it assumes when the needle bar is in its lowermost position; Fig. 5 is a view similar to Fig. 3 showing the needle bar mechanism at the beginning of the movement during which the loop is being formed for the passage of the shuttle; and Fig. 6 is a view similar to Fig. 3 showing the lowermost position of the needle bar during the passage of the shuttle through the loop.

Referring more particularly to the drawings, 1 indicates a portion of the bracket arm which may be of any suitable construction, having at its free end a head 2 pro-

vided with a chamber in which the needle bar mechanism is arranged.

Journalized in the bracket arm 1 is a rotary driving shaft 3 provided at its forward end with a crank consisting, as herein shown, of a disk 4 provided with a crank-pin or wrist-pin 5. To the wrist-pin 5 is jointed one end of a lever 8 pivoted near its middle at 9 to the outer or free end of a swinging link 7 which is pivoted at 6 to the one side of the head or frame 2, preferably at a point above the horizontal plane of the driving shaft 3, said lever being jointed at its other end at 11 to the upper end of a pitman 10 which is jointed at its lower end at 12 to the needle-bar 13 reciprocating in a guide or bushing 14 mounted in the head 2, said needle-bar carrying at its lower end the needle 15. In the construction of the invention as herein illustrated the distance between the axis of the pivot 6 and the axis of the pivot 9 is slightly greater than the distance between the axis of the said pivot and the axis of the driving shaft 3. Also the distance between the axis of the crank-pin or wrist-pin 5 and the axis of the pivot 9 is preferably slightly greater than the distance between the axis of the said crank-pin or wrist-pin and the axis of the driving shaft 3. By virtue of this arrangement of the pivots 5, 6 and 9 relative to the axis of the driving shaft 3, the axis of the pivot 9, when the needle-bar is at its lowest position, occupies a point which is slightly above the axis of the shaft 3, as will be seen by reference to Figs. 5 and 6.

The needle operates through a bed 16 of any suitable construction and co-operates with a reciprocating or vibrating shuttle 17 located below the bed and operated in a well known manner. The cloth is held by the usual presser foot 23 carried by the presser bar 18 controlled by a cam lever 19 which co-operates with the end of a bar 20 guided in the head, the presser foot being moved to its lowermost position by a spring 21. Also arranged on the bar 20 is a guide 22 for the thread which leads from the tension device 24 after being passed through an opening 23^a in the plate 24^a which closes the chamber of the head 2.

Another feature of this invention is the take-up device which embodies an arm 25 extending laterally and forwardly from the pitman link 10 in proximity to the lower

pivot of the latter and thence outwardly at 26 through a straight slot 27 in the face plate 24^a, the outer end of the arm being provided with an opening 28 having a lateral entrance slot through which the thread is introduced into the opening 28. In other words the take-up arm 25 is attached to the pitman 10 in proximity to the pivotal connection of the latter with the needle-bar 15.

Assume the parts are in the positions shown in Fig. 3, a rotation of the crank 4 in the direction of the arrow in this figure will move the crank or wrist pin 5 to the right and exert upon the pivot 11 a substantially straight and downward pull until the parts reach the positions shown in Fig. 4. As this movement of the pitman is substantially straight, it communicates to the needle bar a powerful movement while the needle is entering the goods. After the goods have been penetrated by the needle, the lever 8 is swung on its axis to swing to the left at its lower end and swings the upper end 20 of the pitman 10 to the right or forwardly on an arc which has the effect of raising the needle bar slightly to the position shown in Fig. 5 in order to form a loop through which the shuttle 17 is to pass. During this 25 movement of the pitman link 10, the thread guide opening 28 of the take-up arm 25 tilts downward with the swinging pitman 10 from the position shown in Fig. 4, thus paying out a certain amount of thread. A further 30 movement of the upper end of the pitman 10 to the right then follows, causing the needle bar and needle to make a dip or slight downward movement, the dwell position of which is shown in Fig. 6. During this dip or downward movement, the thread guiding portion 26 of the take-up also tilts farther downward, thus paying out plenty of thread but not much more than is required for the 35 passage of the shuttle through the loop. When the pitman link 10 and the take-up reach the position shown in Fig. 4, the continued movement of the crank 4 shifts the swinging link 7 and the pivoted lever 8 upwardly, the said link causing the lever to move swiftly on the crank or wrist pin 5, thus elevating the needle bar quickly and at a time when it has no work to perform. The take-up also acts during this movement to take up the slack in the thread.

It will be understood that the take-up arm 25, which is attached to the pitman 10 in proximity to the jointed connection of the latter with the needle-bar 13, follows the up-and-down or vertically reciprocating movements of said needle-bar, and also follows the tilting movements of the said pitman,

so that the thread-guiding portion 26 of the said take-up arm will let off just enough thread required for the formation of a loop for the shuttle to pass through and in proper time so that there will be no surplus slack thread, and will quickly tighten the loop on the upward movement of the needle-bar as the parts move from the position shown in Fig. 6 to the position shown in Fig. 3.

From the foregoing it will be seen that there has been provided a needle bar mechanism embodying a plurality of links or levers so arranged and constructed that they may be compactly located within the hollow head of the bracket arm of a sewing machine in proximity to the needle bar. These levers or links are of simple construction and do not require fine and accurate adjustment in the assembling of the machine. There are no parts to get out of order due to wearing action. The needle bar is given a slow, steady and powerful movement during the passage of the needle through the goods and a quick movement during the withdrawal of the needle from the goods. The needle partakes of a small dip in order to permit the formation of the loop through which the shuttle is to pass and the take-up is so connected to the needle bar mechanism that all extra parts are eliminated and the thread paid out or taken up at the proper times. The arrangement of the take-up also enables the machine to run backward without any breaking of the thread, thus permitting the user of the sewing machine to anchor or fasten the thread after the seam has been finished.

What I claim as my invention and desire to secure by Letters Patent is:

In a sewing machine, the combination with a rotating crank, of a lever jointed at one end to said crank, a swinging link pivoted at one end to the machine head or frame and to the free end of which swinging link the said lever is pivoted near its middle, a pitman jointed at its upper end to the end of said lever farthest from the jointed connection of said lever with said crank, a needle-bar to which the lower end of said pitman is jointed, and a take-up arm mounted at the lower part of said pitman in proximity to the jointed connection of the latter with said needle-bar so that said take-up arm follows the vertical reciprocating movements of the said needle-bar and the tilting movements of said pitman.

JOHN HEBERLING.
